CYLINDER LOCK

Phillip W. Olson, Chicago, Ill.

Application April 8, 1943, Serial No. 482,346

2 Claims. (Cl. 70—364)

This invention relates in general to locks and more particularly to a tumbler type cylinder lock highly resistant to "picking."

So-called "pick-proof" locks prior to this invention usually were dependent upon a large number of tumblers or other complicated means for their security and resistance to "picking," which construction is expensive, whereas the novel construction of the present invention includes simple means whereby the use of relatively few tumblers and correspondingly low manufacturing cost provide ample security and high degree of resistance to "picking."

The principal object of the invention is to provide a tumbler lock including a plurality of relatively few detent-controlled tumblers.

A further object of the invention is the provision of a cylinder lock having detent-controlled tumblers of which both ends thereof are applicable for locking the barrel and cylinder.

A further object of the invention is to provide a plurality of tumblers capable of being urged in two directions from their central unlocked position.

Further objects and advantages of the invention will be apparent in one embodiment herein-after described, in which:

Fig. 1 is a side elevation of the lock assembly.

Fig. 2 is a typical key for operating the lock shown Fig. 1.

Fig. 3 is an enlarged cross-sectional view of the lock taken through section lines 3—3, Fig. 1.

Fig. 4 is an enlarged cross-sectional view of the key taken through section lines 4—4, Fig. 2.

Fig. 5 is an enlarged perspective view of the tumbler elements of the lock.

Fig. 6 is an enlarged cross-sectional elevation of the lock taken through section lines 6—6, Fig. 3 and showing the key in proper relation to the lock.

For the purpose of illustration, the type lock shown and described is for the use of a key having unrelated serpentine grooves in its opposite sides, and although this showing is a preferred construction, it will appear from the following description that locks for other type keys are equally applicable.

Referring to Fig. 1, the barrel or housing 1 serves to retain the elements of the lock. A cap 2 closely fitted over the barrel contains the key-hole. A conventional bolt 3 is integrally secured to the rotatable cylinder 4 and is adapted to engage a strike plate, not shown.

Referring to Figs. 2 and 4, the key 5 is provided with a rectangular shank 6 having unrelated ser-

pentine grooves 7 in each side thereof. The barrel 1 has in its inside periphery, two pair of oppositely disposed grooves 8 running parallel to its axis.

5 A cylinder 4 is constructed of two half sections and held together by means of two snap rings 9 fitting in appropriate grooves in each end of the cylinder, shown in Fig. 6. The cylinder is adapted to rotate freely within the barrel 1. A cylindrical projection 10 of the cylinder extends through a bearing ring 11 which is retained in proper position by a snap ring 12. The bolt 3 is integrally attached to the end of the projection 10 for locking purposes.

15 Referring to Fig. 5, each tumbler 13 is provided with a detent projection 14 and a key follower 15 positioned opposite the detent. The key follower in each tumbler is positioned to correspond with a predetermined formation of the serpentine grooves 7 in the key, the action of which will be hereinafter described. Each tumbler is placed in its corresponding slot 16 in the cylinder 4 which extends through the cylinder at right angles to the axis of rotation of the cylinder.

20 25 A detent plunger 17 having a pointed end and a spring 18 are retained in the cylinder in an appropriate hole 19. The pointed end of the plunger is adapted to slidably engage the detent projection 14 of each corresponding tumbler.

30 It is now apparent from Fig. 3 that each tumbler is capable of reciprocable movement in its slot 16 and that the plunger 17 will urge the tumbler in either direction depending upon its initial movement over the central point of the projection 14.

35 In operation and assuming that the key followers 15 have been positioned to suit a corresponding key, it will be seen from Fig. 6 that one end of each tumbler will engage a groove 8 and thus prevent the cylinder 4 from turning in the barrel 1. When the key shown in Fig. 6 is inserted, the lateral surfaces of the serpentine groove 7 will engage the key follower's 15 and withdraw each tumbler a predetermined distance to free its end 40 from the grooves 8 and thus enable the key to turn the cylinder 4 within the barrel 1, which normally would unlock the bolt 3 from a strike plate.

The usual practice of "picking" locks is dependent upon either vibrating or moving the tumblers and disengaging their ends from locking grooves. In the present invention any attempt at moving the tumblers to predetermined positions would be defeated by virtue of the detent action previously described, as it can easily be

seen if a particular tumbler is withdrawn sufficiently far to disengage one of its ends from the cylinder groove and the plunger 17 reaches the peak of the projection 14 of the tumbler, the plunger, urged by spring 18, will throw the tumbler in the opposite direction and thus engage the opposite end of the tumbler in the groove of the cylinder. Therefore, any attempt to operate or "pick" even a small plurality of tumblers without a key is impractical if not impossible.

Although the lock described herein shows three tumblers, it is to be understood that a smaller or larger number of tumblers may be used without departing from the scope of the invention.

Having described my invention, I claim:

1. A cylinder lock comprising a casing having a key-operable rotatable cylinder affixed therein, said casing having a plurality of tumbler slots therein, a plurality of key-operable tumblers slidably retained in said cylinder, each end of said tumblers adapted to engage corresponding said slots, each said tumbler provided with an integral

detent projection, spring-actuated detent means for normally and independently engaging said projection and urging each said tumbler in either direction from a predetermined neutral position to engage one end of each tumbler in a corresponding said slot to lock said cylinder to said casing.

2. A cylinder lock comprising a casing having a key-operable rotatable cylinder affixed therein, 10 said casing having a plurality of tumbler slots therein, a plurality of key-operable tumblers slidably retained in said cylinder, each end of said tumblers adapted to engage corresponding said slots, a detent projection integral with each said tumbler, a plurality of spring-actuated plungers 15 for normally and independently engaging each said projection for urging each said tumbler in either direction to engage either end of each tumbler in a corresponding said slot to lock said cylinder to said casing.

PHILLIP W. OLSON.
